UNITED STATES PATENT OFFICE.

HARVEY P. MALLISON, OF LANSDOWNE, PENNSYLVANIA, ASSIGNOR TO THE
M. A. FURBUSH & SON MACHINE COMPANY, OF CAMDEN, NEW JERSEY.

WARPING OR REELING MACHINE.

SPECIFICATION forming part of Letters Patent No. 513,481, dated January 23, 1894.

Application filed October 6, 1893. Serial No. 487,337. (No model.)

To all whom it may concern:

Be it known that I, HARVEY P. MALLISON, a citizen of the United States, residing at Lansdowne, in the county of Delaware and 5 State of Pennsylvania, have invented certain new and useful Improvements in Warping or Reeling Machines, of which the following is a specification.

My invention has relation to warping or 10 reeling machines; and it relates more particularly to the construction and arrangement of appliances for reeling yarn or fibrous material and beaming the same to constitute warp in the weaving of a fabric.

15 Hitherto in the reeling of the yarn or thread to constitute the warp for the weaving operation, it has been customary to conduct or lead the ends of the yarn or thread from spools or bobbins mounted in a creel or frame, 20 through a supported heck or lease and sectional reed to a reel to cause the thread or yarn to be wound in sections onto the cross-arms thereof, within range of detachable pins mounted in and projecting from the arms until the spools or bobbins of the creel or frame 25 were depleted and the cross-arms of the reel were provided with their full quota of said material, when it was wound off of the reel onto a beam to become the warp of a loom 30 for the weaving of a fabric. The use of detachable pins in connection with the cross-arms of the reel has long been regarded as exceedingly objectionable, for many reasons and more particularly, because in the winding of the yarn or fibrous material onto the 35 reel at a high rate of speed there is a constant tendency for the material to become entangled with the pins and thus for the thread or yarn to break short or the pins to kink the 40 same in such manner as to deteriorate the strength thereof in the one instance or to necessitate in the other the stopping of the reel to take up and unite broken ends. Moreover, such mode of winding the yarn or fibrous 45 material onto a reel, due to its nature and constitution has many further objections and disadvantageous features connected therewith, and among them, that of the intermeshing and hugging of the individual threads to 50 the neighboring threads thereof, and the lack of regularity in tension, so that there is ab-

normal stretching of some of the threads and slackening or sagging of others, whereby in unwinding from the reel onto a beam, due to such lack of tension and the use of detachable pins, it has been found in extended practice that the material is very apt to be so deteriorated as to give a warp unfit for subsequent use. In a word, lack of uniformity or regularity in the reeling of the yarn or 60 thread affects the warp in the weaving, to such an extent as to produce in certain parts loose and in other parts tight or drawn meshes in the article and consequently depreciating the market value thereof. 65

The principal objects of my invention are first, to overcome the above mentioned objections and disadvantageous features in the winding or reeling of yarn, thread or fibrous material to constitute warp in weaving operations; and to provide a comparatively simple, durable and efficient warping-reel, for giving a superior resultant material and in such state or condition as to furnish a uniform type or quality of warp; second, to provide a warping-reel with attachments or devices adjustably connected with the cross-arms thereof and so arranged as that the thread or yarn in the reeling operation is built up in regular lays onto one another into 70 substantially truncated cones and in such manner as that in the formation of one of such figures or forms it will become a form or guide for the building or laying up in regular sequence of a series of such cone-shaped deposits of the yarn or fibrous material onto the 75 respective cross-arms of the reel in the rotation thereof until the spools or bobbins of the creel or frame have been depleted or until the cross-arms of the reel have been completely 80 covered and in such manner as to present a smooth cylindrical surface, when the same is transferred in such state or condition to a beam to constitute warp for use in the weaving operation; third to provide a warping-reel 85 adapted to cone the yarn or thread thereon and provided with mechanism adapted to move automatically step by step in one direction in the laying or building up of the thread or yarn into cone-shaped figures or forms 90 thereon; fourth, to provide a warping-reel 95 adapted to improve the winding of the yarn 100

or thread and with the absence of broken threads or of having to stop the reel to take up and unite broken ends in the unwinding of the same onto a beam to become warp; and 5 fifth, to provide a reel or frame and an adjustably supported heck or lease and sectional reed for employment in connection with a rotatable coning reel and mechanism for detachably supporting and rotating a 10 beam for the reception of the thread or yarn from the reel in a reverse step-by-step movement of the same, and the said mechanism so constructed and arranged as that the warping and beaming operations are appreciably 15 improved and a superior quality of warp for weaving is obtained, due to the uniformity of tension maintained throughout the winding or reeling of the yarn or fibrous material.

My invention stated in general terms, 20 consists of a warping-reel provided with attachments adjustably connected therewith and so arranged as that the yarn or fibrous material is formed in regular and united sequence thereby into cones presenting a smooth cylindrical surface for transfer therefrom to a beam to become warp.

My invention further consists in the improvements hereinafter described and claimed.

30 The nature, general features and scope of my invention will be more fully understood from the following description taken in connection with the accompanying drawings forming part hereof; and in which—

35 Figure 1, is a perspective view of a warping or reeling machine embodying features of my invention. Fig. 2, is a front elevational view of the reel detached from its standards with the adjustable coning attachments of my in- 40 vention in application thereto and showing also the mode of building or laying up the yarn or fibrous material onto the reel accord- 45 ing to the principle involved in and by my invention. Fig. 3, is a side elevational view 50 partly in section of one of the cross-arms of the warping-reel and also a longitudinal section through the yarn or threads wound thereon, serving to illustrate the general appear- 55 ance of the respective groups and overlap- 60 ping layers of thread or yarn comprising the series of united conical figures or forms there- 65 of constituted by the winding in the rotation of the reel; and Fig. 4, is a perspective view showing in detail the adjustable attachment 70 or device for application to each of the cross-arms of the reel as illustrated in Fig. 1, for permitting in the rotation of the reel, the coning of the yarn or fibrous material and so as to assume the form illustrated in Fig. 2, in such 75 winding of the same thereon.

Referring to the drawings with special reference to Fig. 1, A, is a platform provided with rails a and a' . This platform supports a creel or frame adapted for the reception of the groups of spools or bobbins a^2 , engaging recesses provided in the series of vertical supports a^3 , of the frame therefor. The creel or

frame A' , may be provided with casters a^4 , for affording handy means for effecting the movement of the same to required positions on the platform A.

b , is a heck or a sectional reed detachably supported to a bracket b' , and carrying a guide or lease reed b^2 . This supporting bracket b' , is mounted on a rack or standard b^3 , which is provided with a series of feet b^4 .

C , is a reel. c and c' , are the respective end standards thereof provided with base cross-pieces c^2 , and a top cross-piece c^3 .

c^4 , is a series of grooved wheels journaled to the end standards c and c' , and adapted to engage with and travel on the rails a and a' , of the platform A.

The reel C , comprises circular frames C' , C^2 and C^3 , mounted on a shaft c^5 , which is journaled to the standards c and c' . The frames C' , C^2 and C^3 , of the reel are provided with a series of cross-arms or bars c^6 , as clearly illustrated in Fig. 1.

c^7 and c^8 , are end hangers carrying grooved rollers c^9 and c^{10} .

c^{11} , c^{12} and c^{13} , are pulleys or wheels rigidly mounted on a shaft c^{14} , held in bearings c^{15} , of the end standards c and c' .

c^{16} and c^{17} , are belts engaging the respective pulleys c^{11} and c^{13} , the grooved rollers c^9 and c^{10} , and the grooved end frames C' and C^3 , of the reel C .

c^{18} , is a belt engaging the pulley or wheel c^{12} , having motion imparted thereto from any suitable source of power, and which in turn communicates motion to the shaft c^{14} , to rotate the reel C , through the intervention of the pulleys c^{11} and c^{13} , grooved rollers c^9 and c^{10} , and the circular end frames C' and C^3 , engaged by the belts c^{16} and c^{17} .

D , is a longitudinal rack secured to the platform A, between the tracks a and a' , thereof.

d' , is a worm mounted on the shaft c^5 , and meshing with a gear-wheel d^2 , secured to a vertical-shaft d^3 , which is provided at the upper extremity with a hand-wheel d^4 , and at the lower extremity with a pinion d^5 , adapted to mesh with the rack D .

Beneath or adjacent to the gear-wheel d^2 , and connected with the shaft d^3 , is a box d^6 , and a collar or bracket d^7 , and with an eccentric or cam lever d^8 , adapted to be operated within the box d^6 , so as to disengage the worm d' , from the gear-wheel d^2 .

The hand-wheel d^4 , is adapted to be operated as required during the rotation of the reel C , to move it a certain distance with respect to the position it occupies through the automatic movement of the mechanism for effecting the rotation of the reel C , or to return the same by means of the rack and pinion to its initial position for any cause in the reeling of the yarn or fibrous material.

E , represents a series of adjustable coning attachments or devices of my invention, each of which is pivoted at e , to a cross-arm c^6 , of the reel C . This coning device E , comprises

in the present instance, as shown in Figs. 1 and 4, a divided casting or bracket with depending slotted curved arms or yokes e' and e^2 , engaged by clamping or fastening means e^3 , of any preferred form and the divided portion of the casting or bracket E, straddling each of the series of cross-arms c^6 .

f , is a longitudinal graduated strip, plank or rod connected with the platform A, and laid off so as to be enabled to determine with accuracy the required distance that the reel must travel in one direction in order to lay or build up each cone of yarn or fibrous material onto the respective cross-arms c^6 , of the reel C, in the rotation thereof and in such manner as that the threads or yarn will overlap onto one another as illustrated in Fig. 3, in the formation of each of the cones of the series covering the entire surface or area of the reel C; and moreover present a smooth cylindrical exterior surface, whereby a superior winding off of the same onto a beam is obtained and in the manner to be hereinafter described.

f' , is a spring controlled or adjustable indexed-finger or pointer extending from a bracket f^2 , near the base of the standard c , of the reel as clearly illustrated in Fig. 1.

It should be borne in mind that upon the complete formation of the first cone of yarn or analogous material onto the cross-arms c^6 , of the reel C, the eccentric or cam-lever d^2 , is actuated to throw the worm d' , out of engagement with the gear-wheel d^2 , when the reel is moved to the point 2, of the graduated strip, rod or plank f , with the spring controlled pointer or finger f' , depressed sufficiently to engage positively with the strip, rod or plank f , at the point 2, thereof. The pointer or finger f' is then released in order that by throwing the gear-wheel d^2 , again into engagement with the worm d' , by means of the lever d^3 , the pinion d^4 , will engage the rack D, and move the same step-by-step and therewith the reel C, the required distance to form another truncated cone of yarn or fibrous material onto the cross-arms c^6 , of the reel in overlapping layers onto one another and so as to merge with the previously formed cone thereon in such manner as to present a surface and body built or laid up in the manner as illustrated in Figs. 2 and 3. Consequently in regular succession each cone can be formed of yarn or fibrous material from the spools or bobbins of the creel or frame A', onto the cross-arms c^6 , of the reel C, until the reel is completely built up as clearly illustrated in Fig. 2, ready to be transferred onto a beam to become warp for subsequent use in weaving operations and in the manner to be hereinafter fully explained.

g , is a grooved or channeled base-plate to which is detachably secured a standard g' , provided with a jaw forming a bearing g^2 , and with a removable pin or stud g^3 .

g^4 and g^5 , are frames or standards having wings or arms g^6 and g^7 .

g^8 , is a shaft journaled to the frames g^4 and g^5 , and provided with a gear-wheel g^9 , meshing with a pinion g^{10} , mounted on a shaft g^{11} , which is suitably journaled to the wings or arms g^6 and g^7 , and having mounted thereon loose and fast pulleys g^{12} and g^{13} .

g^{14} , is a swinging pawl mounted on a cross-rod g^{15} , secured into the standards g^4 and g^5 .

g^{16} , is a belt shifting mechanism connected with the projecting arms or wings g^{20} and g^{21} .

g^{17} , is a belt engaging the loose pulley g^{13} .

g^{18} , is a vertically adjustable bearing plate connected with the end standard g^5 .

G , is a beam detachably engaging the bearings g^2 and g^{19} , of the standards g^4 and g^5 , for beaming the yarn or fibrous material from the warping reel C.

The operation of the several appliances or devices hereinbefore described from the drawings will be fully understood without further explanation. In Figs. 1, 2 and 3, the preferred operation is clearly illustrated that takes place in the coning of the yarn onto the reel by the rotation thereof, and which embraces one of the essential features of my present invention. The beaming of the yarn, it will be understood is carried out with due regard to required tension of the reel with respect to the beam in order to insure uniformity in the transfer of the fibrous material from the reel C, in entirety onto the beam G. It may, however, be here remarked that in the beaming operation the rotation of the reel C, is reversed and also that the same is allowed to travel in an opposite direction to that required for the reeling of the material until the point at which the reeling of one section of the yarn onto the same is reached, when the entire contents of the reel will have been wound off onto the beam G. During beaming, the belt c^{18} , will be disengaged from the pulley c^{12} , and weights may be applied to the belts c^{16} and c^{17} , in order to produce the required friction between the same and the end circular frames C' and C^3 , of the reel C, so that in the drawing off of the yarn from the reel C, onto the beam G, it may be accomplished under a positive or reliable tension, and while the reel as already explained, is returning step-by-step to its initial position, being arrived at when the point l , of the graduated strip, rod or plank f , is reached for commencing again by applying the belt c^{18} , to the pulley c^{12} , the reeling operation.

Having thus described the nature and objects of my invention, what I claim as new, and desire to secure by Letters Patent, is—

1. A warping-reel provided with a series of cross-arms and each of said arms provided with a bifurcated casting or bracket having slotted-arms or yokes, and a clamping device extending through said slotted arms or yokes and each cross-arm for adjusting said casting or bracket to required position and means for rotating said reel, substantially as and for the purposes set forth.

2. A warping-reel provided with a series of

cross-arms, a bifurcated casting or bracket pivoted to each of said cross-arms and having rear depending yokes straddling each of said cross-arms and a clamping-device extending through said yokes and cross-arms, substantially as and for the purposes set forth.

3. A movable frame, a rotatable warping reel mounted therein and provided with coning attachments and an axis having a worm thereon, a stationary rack, a shaft carried by said frame and provided with a pinion adapted to mesh with said rack, a worm-wheel mounted on said shaft and adapted to mesh with said worm, and means for engaging and disengaging said worm and worm-wheel, substantially as and for the purposes set forth.

4. A movable frame provided with rollers engaging rails, a warping reel mounted in said frame and provided with coning attachments and an axis having a worm thereon, a stationary rack, a shaft carried by said frame and provided with a pinion adapted to mesh with said rack, a worm-wheel mounted on said shaft and adapted to mesh with said worm and an eccentric lever for engaging and dis-

engaging said worm and worm-wheel, substantially as and for the purposes set forth.

5. A movable frame, a rotatable warping reel mounted therein and provided with coning attachments and an axis having a worm thereon, a stationary rack, a shaft carried by said frame and provided with a pinion adapted to mesh with said rack, a worm-wheel mounted on said shaft and adapted to mesh with said worm, a hand-wheel secured to said shaft and adapted to be operated during the rotation of said reel to move the same a required distance with respect to a particular position occupied by said reel or to return the same to its initial position, and means for engaging and disengaging said worm and worm-wheel, substantially as and for the purposes set forth.

In testimony whereof I have hereunto set my signature in the presence of two subscribing witnesses.
